US00D853443S

(12) United States Design Patent (10) Patent No.: US D853,443 S
Chaudhri et al. (45) Date of Patent: * Jul. 9, 2019

(54) DISPLAY SCREEN OR PORTION THEREOF WITH ICON

(71) Applicant: Apple Inc., Cupertino, CA (US)

(72) Inventors: Imran Chaudhri, San Francisco, CA (US); Jonathan P. Ive, San Francisco, CA (US); Wan Si Wan, Sunnyvale, CA (US)

(73) Assignee: Apple Inc., Cupertino, CA (US)

() Term: 15 Years

(21) Appl. No.: 29/675,929

(22) Filed: Jan. 7, 2019

(57) CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is a front view of another embodiment thereof.

The broken lines in the figures show a display screen or portion thereof and form no part of the claimed design.
